UNITED STATES PATENT OFFICE.

ALBERT BEVERLEY, OF GORRINGE PARK, MITCHAM, ENGLAND.

MACHINE FOR BLOWING GLASS BOTTLES, JARS, AND THE LIKE.

1,065,499.

Specification of Letters Patent. Patented June 24, 1913.

Application filed June 15, 1912. Serial No. 703,932.

To all whom it may concern:

Be it known that I, ALBERT BEVERLEY, a subject of the King of Great Britain, residing at 46 Tynemouth road, Gorringe Park, Mitcham, in the county of Surrey, England, have invented new and useful Improvements in Machines for Blowing Glass Bottles, Jars, and the Like, of which the following is a specification.

10 The object of this invention is to provide an improved machine for blowing glass bottles, jars and the like.

The accompanying drawings show a preferred embodiment of my invention but it is obvious that many minor changes may be made therein without going beyond the scope of my invention.

The machine illustrated is capable of making four bottles at one time but this number may be varied.

Figure 1 is a plan of the machine; Fig. 2 is a transverse section; Fig. 3 shows a detail; Fig. 4 is a left hand end view; Figs. 5 and 6 show details; Fig. 7 shows part of the mechanism for operating the molds and neck rings; Figs. 8 to 15 show details. Figs. 1, 4 and 12 are to a smaller scale than the others.

1 is the main shaft having on it four pulleys on which runs the driving belt. The first pulley 2 is on a sleeve on the shaft; the second 3 is a loose pulley, the third 4 is fast with the shaft and the fourth 5 is on a sleeve. The fourth and fifth are narrow pulleys so that the belt may drive both together. Fast on the shaft are two pinions 6 one at either end of the machine; these gear with vertical racks 7 depending from the table 8 which is thus capable of an up and down movement in guides on the frame of the machine. The table carries four parison molds 9. The molds may simply be dropped into sockets 10 on the table and these sockets are preferably capable of vertical movement with regard to the table, being mounted on springs 11 and carried by pistons 12 moving in cylinders 13 open to the atmosphere. This allows any mold to stop short of its highest position if too great a charge has been placed in it. Hereafter I will describe the machine as if there were only one mold and one socket on the table for however many sockets there be on the table, that is however many be the bottles than can be blown at one operation, the mechanisms

will simply be repetitions of that used for one bottle.

Above the socket 10 is a stationary hollow core rod 14 so situated that as the table rises the core rod enters the mass of glass 60 in the parison mold as shown in Fig. 3. It must be understood that to save drawing Fig. 2 shows not only a parison mold with its charge below the core rod but also the finishing mold in position around the core 65 rod and that such finishing mold must be withdrawn and the finished bottle removed from the core rod before the table rises.

Fast with the pulley 5 is a pinion 15 meshing with a pinion 16 on a shaft 17 on which 70 is a bevel wheel 18 gearing with a bevel wheel 19 on a vertical spindle 20. The socket of the parison mold is supported by a pinion 21 meshing with a pinion 22 which is free to slide up and down the spindle 20. 75 As the table 8 rises, an arm 23 upon it raises the pinion 22 which is thus always level with the pinion 21 and therefore the mold 9 is rotated on its axis during the rise of the table. When the table reaches its 80 highest position it comes against a lever 24 (see Fig. 4) pivoted to an adjustable block 25 and connected by a slotted link 26 to a lever 27 fulcrumed on the frame at 28. The lower end of this lever moves a slide 29 85 along a fixed guide 30 and to this slide is connected one end of a link 31 pivoted to an arm 32 which can turn on a fixed pivot 33. The other end of the link 31 is hinged to a rod 34 running along the rear of the machine and connected by a bar 35 to the belt shifter 36. The effect of the parts numbered from 24 to 36 is that when the table strikes lever 24 the belt shifter is moved to the right 90 and the belt is removed from pulleys 4 and 5 to pulley 2. The table is therefore raised no higher. In the path of the table and at each end thereof I arrange a detent or slide 37 connected by cross links 38 (see Figs. 4 and 5) to a detent 39 in such a way that 95 when the table strikes slides 37 and moves them toward the front of the machine, the detents 39 move rearward beneath the table and hold it up. While the table is thus retained, the charge in the mold is marvered as follows:—As the belt shifter moves to the right an arm 40 (see Fig. 1) upon it comes against the rear end of a lever 41 and rocks it on its pivot 42. To the rear end of this lever is hinged a link 43 connected 100

110

to the bottom of a lever 44 by which a bevel wheel 45 on a shaft 46 can be moved into engagement with a bevel pinion 47 fast with the pulley 2. On the shaft 46 are two bevel pinions 48, each of which has teeth around one half only of its periphery and with these mutilated pinions meshes a bevel wheel 49 which is moved on its shaft 50 by a lever 51 pivoted at 52 and having its lower end hinged to the lever 41. This shaft 50 has fast on it a spur wheel 53 which meshes the pinion 16 already described. As therefore the pulley 2 rotates the shaft 50 is rotated first in one direction and then in the other and the mold is consequently rotated first in one direction and then in the other, marvering the charge within it. If the machine be required to make bottles other than cylindrical, the marvering may be obviated by removing the fork on lever 51 which embraces bevel wheel 49. On the shaft 46 moreover is a pinion 54 gearing with a pinion 55 on a cam shaft 56 on which is a cam 57 adapted to move to the left a rod 58 which engages by pins 59 (see Figs. 1 and 4) the rear ends of a pair of horizontal levers 60 the front ends of which have upon them inclines 61 which bear against the lower ends of levers 62 turning on horizontal pivots 63 while their upper ends engage the slides 37. When therefore the rod 58 is shifted to the left the slides 37 are moved rearward and the detents 39 are withdrawn. The table therefore falls by its own weight and the charge is left hanging to the core rod and neck ring as seen in Fig. 6. The neck ring 64 just referred to is constructed in two halves which are closed around the core rod before the table begins to rise as will be described later and the glass is forced by the rise of the mold up between the neck ring and the core rod. As soon as the table has fallen sufficiently to bring the top of the parison mold below the bottom of the charge, the finishing mold may be closed upon the half formed bottle. This is effected as follows:—The mold is formed in two halves 65 carried by arms 66 (see Figs. 2 and 7) which can turn around a pillar 67 and linked by links 68 to a longitudinal bar 69 to which are attached the rods 70 of pistons 71 moving in cylinders 72 arranged one at each end of the machine and supplied with compressed air by a supply pipe 73. Each cylinder has an inlet valve 74 in a valve box 75 coöoperating with ports 76 admitting air to each end of the cylinder while 77 are exhaust valves coöoperating with exhaust ports 78 by which the pressure at each end of the cylinders can be relieved. The inlet valves 74 and exhaust valves 78 have at their rear ends arms 79 pivoted to a bar 80 (see Figs. 1 and 8) at the top of a lever 81 pivoted at 82 and having at its lower end a pin 83 between pins 84, 85 on rods 86, 87 held by springs 88 against cams 89, 90 on the cam shaft 56. When the cam 89 moves the rod 86 to the left, the valves 77 are turned so as to put the front ends of the cylinders to exhaust while the inlet valves 74 are turned so as to admit air to the rear of the pistons which therefore move forward bring the bar 69 forward and therefore close the molds as shown in Fig. 2. As soon as the molds are thus closed, I supply air to the core rods; this is effected as follows:—The bar 69 has attached to it a slide 91 (see Figs. 1 and 9) on which is an incline 92 and as the bar moves forward as above described this incline pushes up a valve 93 in a valve box 94 connected to the air pipe 73 so that air can pass to a pipe 95 leading to the top of the core rod which is suitably perforated so that the air can pass into the interior of the glass and below it to the form shown in Fig. 2. The core rod will of course be varied in shape and size to suit the various molds in use and in some cases may have grooves, flats or indentations formed upon it to enable it to hold the glass while the parison mold is descending and the molds closing. The core rod is preferably cooled by oil which is supplied to a chamber 96 and passes down an oval tube 97 (see Figs. 10 and 11) to near the bottom of the core rod and returns up a central pipe 98. Blowing continues until a drop in the cam 90 comes opposite the end of the rod 87 which is then moved to the right by its spring 88 so turning the valves 74 and 77 to move the pistons 71 rearward. This brings back the bar 69 cutting off air from the core rods, putting them to exhaust by port 99 and opening the finishing molds. All this time the belt has remained on pulley 2 but now a wiper 100 on the cam shaft 56 comes against a pivoted catch 101 and lifts it out of a slot 102 in the rod 34 which is then pulled to the left by the spring 103 (see Figs. 1 and 12); this brings the belt on to the loose pulley 3 and the machine stops. The finished bottle can now be taken off the core rod and a fresh parison mold that has had a charge gathered in it meanwhile can be placed on the table. An attendant now moves to the left a starting lever 104 (see Figs. 1 and 12) to which is coupled by a cord 150 passing over a pulley 151 a rocking arm 105 provided with an incline 106 which lifts the rod 34 so that a shoulder 107 on the rod which had been caught by a fixed stop 108 is freed from that stop and the rod is moved to its extreme left position thus shifting the belt on to the pulleys 4 and 5, from which the cycle of operations already described is repeated. The lever 104 has pivoted to its lower end a rod 109 parallel to the rod 34 and carrying two inclines 110 (see Fig. 12) which as this rod moves to the right come against the lower ends of two vertical levers 111 and 112 which are pivoted to the frame 113 and 114 respectively. The levers 111 and 112 are connected by a cord 115 to a lever 116 which is pivoted to the frame 117 and 118 respectively. The lever 116 is connected by a cord 119 to a lever 120 which is pivoted to the frame 121 and 122 respectively. The lever 120 is connected by a cord 123 to a lever 124 which is pivoted to the frame 125 and 126 respectively. The lever 124 is connected by a cord 127 to a lever 128 which is pivoted to the frame 129 and 130 respectively. The lever 128 is connected by a cord 131 to a lever 132 which is pivoted to the frame 133 and 134 respectively. The lever 132 is connected by a cord 135 to a lever 136 which is pivoted to the frame 137 and 138 respectively. The lever 136 is connected by a cord 139 to a lever 140 which is pivoted to the frame 141 and 142 respectively. The lever 140 is connected by a cord 143 to a lever 144 which is pivoted to the frame 145 and 146 respectively. The lever 144 is connected by a cord 147 to a lever 148 which is pivoted to the frame 149 and 150 respectively. The lever 148 is connected by a cord 152 to a lever 154 which is pivoted to the frame 155 and 156 respectively. The lever 154 is connected by a cord 158 to a lever 160 which is pivoted to the frame 161 and 162 respectively. The lever 160 is connected by a cord 166 to a lever 168 which is pivoted to the frame 169 and 170 respectively. The lever 168 is connected by a cord 174 to a lever 176 which is pivoted to the frame 177 and 178 respectively. The lever 176 is connected by a cord 182 to a lever 184 which is pivoted to the frame 185 and 186 respectively. The lever 184 is connected by a cord 190 to a lever 192 which is pivoted to the frame 193 and 194 respectively. The lever 192 is connected by a cord 198 to a lever 200 which is pivoted to the frame 201 and 202 respectively. The lever 200 is connected by a cord 208 to a lever 210 which is pivoted to the frame 211 and 212 respectively. The lever 210 is connected by a cord 218 to a lever 220 which is pivoted to the frame 221 and 222 respectively. The lever 220 is connected by a cord 228 to a lever 230 which is pivoted to the frame 231 and 232 respectively. The lever 230 is connected by a cord 238 to a lever 240 which is pivoted to the frame 241 and 242 respectively. The lever 240 is connected by a cord 248 to a lever 250 which is pivoted to the frame 251 and 252 respectively. The lever 250 is connected by a cord 258 to a lever 260 which is pivoted to the frame 261 and 262 respectively. The lever 260 is connected by a cord 268 to a lever 270 which is pivoted to the frame 271 and 272 respectively. The lever 270 is connected by a cord 278 to a lever 280 which is pivoted to the frame 281 and 282 respectively. The lever 280 is connected by a cord 288 to a lever 290 which is pivoted to the frame 291 and 292 respectively. The lever 290 is connected by a cord 298 to a lever 300 which is pivoted to the frame 301 and 302 respectively. The lever 300 is connected by a cord 308 to a lever 310 which is pivoted to the frame 311 and 312 respectively. The lever 310 is connected by a cord 318 to a lever 320 which is pivoted to the frame 321 and 322 respectively. The lever 320 is connected by a cord 328 to a lever 330 which is pivoted to the frame 331 and 332 respectively. The lever 330 is connected by a cord 338 to a lever 340 which is pivoted to the frame 341 and 342 respectively. The lever 340 is connected by a cord 348 to a lever 350 which is pivoted to the frame 351 and 352 respectively. The lever 350 is connected by a cord 358 to a lever 360 which is pivoted to the frame 361 and 362 respectively. The lever 360 is connected by a cord 368 to a lever 370 which is pivoted to the frame 371 and 372 respectively. The lever 370 is connected by a cord 378 to a lever 380 which is pivoted to the frame 381 and 382 respectively. The lever 380 is connected by a cord 388 to a lever 390 which is pivoted to the frame 391 and 392 respectively. The lever 390 is connected by a cord 398 to a lever 400 which is pivoted to the frame 401 and 402 respectively. The lever 400 is connected by a cord 408 to a lever 410 which is pivoted to the frame 411 and 412 respectively. The lever 410 is connected by a cord 418 to a lever 420 which is pivoted to the frame 421 and 422 respectively. The lever 420 is connected by a cord 428 to a lever 430 which is pivoted to the frame 431 and 432 respectively. The lever 430 is connected by a cord 438 to a lever 440 which is pivoted to the frame 441 and 442 respectively. The lever 440 is connected by a cord 448 to a lever 450 which is pivoted to the frame 451 and 452 respectively. The lever 450 is connected by a cord 458 to a lever 460 which is pivoted to the frame 461 and 462 respectively. The lever 460 is connected by a cord 468 to a lever 470 which is pivoted to the frame 471 and 472 respectively. The lever 470 is connected by a cord 478 to a lever 480 which is pivoted to the frame 481 and 482 respectively. The lever 480 is connected by a cord 488 to a lever 490 which is pivoted to the frame 491 and 492 respectively. The lever 490 is connected by a cord 498 to a lever 500 which is pivoted to the frame 501 and 502 respectively. The lever 500 is connected by a cord 508 to a lever 510 which is pivoted to the frame 511 and 512 respectively. The lever 510 is connected by a cord 518 to a lever 520 which is pivoted to the frame 521 and 522 respectively. The lever 520 is connected by a cord 528 to a lever 530 which is pivoted to the frame 531 and 532 respectively. The lever 530 is connected by a cord 538 to a lever 540 which is pivoted to the frame 541 and 542 respectively. The lever 540 is connected by a cord 548 to a lever 550 which is pivoted to the frame 551 and 552 respectively. The lever 550 is connected by a cord 558 to a lever 560 which is pivoted to the frame 561 and 562 respectively. The lever 560 is connected by a cord 568 to a lever 570 which is pivoted to the frame 571 and 572 respectively. The lever 570 is connected by a cord 578 to a lever 580 which is pivoted to the frame 581 and 582 respectively. The lever 580 is connected by a cord 588 to a lever 590 which is pivoted to the frame 591 and 592 respectively. The lever 590 is connected by a cord 598 to a lever 600 which is pivoted to the frame 601 and 602 respectively. The lever 600 is connected by a cord 608 to a lever 610 which is pivoted to the frame 611 and 612 respectively. The lever 610 is connected by a cord 618 to a lever 620 which is pivoted to the frame 621 and 622 respectively. The lever 620 is connected by a cord 628 to a lever 630 which is pivoted to the frame 631 and 632 respectively. The lever 630 is connected by a cord 638 to a lever 640 which is pivoted to the frame 641 and 642 respectively. The lever 640 is connected by a cord 648 to a lever 650 which is pivoted to the frame 651 and 652 respectively. The lever 650 is connected by a cord 658 to a lever 660 which is pivoted to the frame 661 and 662 respectively. The lever 660 is connected by a cord 668 to a lever 670 which is pivoted to the frame 671 and 672 respectively. The lever 670 is connected by a cord 678 to a lever 680 which is pivoted to the frame 681 and 682 respectively. The lever 680 is connected by a cord 688 to a lever 690 which is pivoted to the frame 691 and 692 respectively. The lever 690 is connected by a cord 698 to a lever 700 which is pivoted to the frame 701 and 702 respectively. The lever 700 is connected by a cord 708 to a lever 710 which is pivoted to the frame 711 and 712 respectively. The lever 710 is connected by a cord 718 to a lever 720 which is pivoted to the frame 721 and 722 respectively. The lever 720 is connected by a cord 728 to a lever 730 which is pivoted to the frame 731 and 732 respectively. The lever 730 is connected by a cord 738 to a lever 740 which is pivoted to the frame 741 and 742 respectively. The lever 740 is connected by a cord 748 to a lever 750 which is pivoted to the frame 751 and 752 respectively. The lever 750 is connected by a cord 758 to a lever 760 which is pivoted to the frame 761 and 762 respectively. The lever 760 is connected by a cord 768 to a lever 770 which is pivoted to the frame 771 and 772 respectively. The lever 770 is connected by a cord 778 to a lever 780 which is pivoted to the frame 781 and 782 respectively. The lever 780 is connected by a cord 788 to a lever 790 which is pivoted to the frame 791 and 792 respectively. The lever 790 is connected by a cord 798 to a lever 800 which is pivoted to the frame 801 and 802 respectively. The lever 800 is connected by a cord 808 to a lever 810 which is pivoted to the frame 811 and 812 respectively. The lever 810 is connected by a cord 818 to a lever 820 which is pivoted to the frame 821 and 822 respectively. The lever 820 is connected by a cord 828 to a lever 830 which is pivoted to the frame 831 and 832 respectively. The lever 830 is connected by a cord 838 to a lever 840 which is pivoted to the frame 841 and 842 respectively. The lever 840 is connected by a cord 848 to a lever 850 which is pivoted to the frame 851 and 852 respectively. The lever 850 is connected by a cord 858 to a lever 860 which is pivoted to the frame 861 and 862 respectively. The lever 860 is connected by a cord 868 to a lever 870 which is pivoted to the frame 871 and 872 respectively. The lever 870 is connected by a cord 878 to a lever 880 which is pivoted to the frame 881 and 882 respectively. The lever 880 is connected by a cord 888 to a lever 890 which is pivoted to the frame 891 and 892 respectively. The lever 890 is connected by a cord 898 to a lever 900 which is pivoted to the frame 901 and 902 respectively. The lever 900 is connected by a cord 908 to a lever 910 which is pivoted to the frame 911 and 912 respectively. The lever 910 is connected by a cord 918 to a lever 920 which is pivoted to the frame 921 and 922 respectively. The lever 920 is connected by a cord 928 to a lever 930 which is pivoted to the frame 931 and 932 respectively. The lever 930 is connected by a cord 938 to a lever 940 which is pivoted to the frame 941 and 942 respectively. The lever 940 is connected by a cord 948 to a lever 950 which is pivoted to the frame 951 and 952 respectively. The lever 950 is connected by a cord 958 to a lever 960 which is pivoted to the frame 961 and 962 respectively. The lever 960 is connected by a cord 968 to a lever 970 which is pivoted to the frame 971 and 972 respectively. The lever 970 is connected by a cord 978 to a lever 980 which is pivoted to the frame 981 and 982 respectively. The lever 980 is connected by a cord 988 to a lever 990 which is pivoted to the frame 991 and 992 respectively. The lever 990 is connected by a cord 998 to a lever 1000 which is pivoted to the frame 1001 and 1002 respectively. The lever 1000 is connected by a cord 1008 to a lever 1010 which is pivoted to the frame 1011 and 1012 respectively. The lever 1010 is connected by a cord 1018 to a lever 1020 which is pivoted to the frame 1021 and 1022 respectively. The lever 1020 is connected by a cord 1028 to a lever 1030 which is pivoted to the frame 1031 and 1032 respectively. The lever 1030 is connected by a cord 1038 to a lever 1040 which is pivoted to the frame 1041 and 1042 respectively. The lever 1040 is connected by a cord 1048 to a lever 1050 which is pivoted to the frame 1051 and 1052 respectively. The lever 1050 is connected by a cord 1058 to a lever 1060 which is pivoted to the frame 1061 and 1062 respectively. The lever 1060 is connected by a cord 1068 to a lever 1070 which is pivoted to the frame 1071 and 1072 respectively. The lever 1070 is connected by a cord 1078 to a lever 1080 which is pivoted to the frame 1081 and 1082 respectively. The lever 1080 is connected by a cord 1088 to a lever 1090 which is pivoted to the frame 1091 and 1092 respectively. The lever 1090 is connected by a cord 1098 to a lever 1100 which is pivoted to the frame 1101 and 1102 respectively. The lever 1100 is connected by a cord 1108 to a lever 1110 which is pivoted to the frame 1111 and 1112 respectively. The lever 1110 is connected by a cord 1118 to a lever 1120 which is pivoted to the frame 1121 and 1122 respectively. The lever 1120 is connected by a cord 1128 to a lever 1130 which is pivoted to the frame 1131 and 1132 respectively. The lever 1130 is connected by a cord 1138 to a lever 1140 which is pivoted to the frame 1141 and 1142 respectively. The lever 1140 is connected by a cord 1148 to a lever 1150 which is pivoted to the frame 1151 and 1152 respectively. The lever 1150 is connected by a cord 1158 to a lever 1160 which is pivoted to the frame 1161 and 1162 respectively. The lever 1160 is connected by a cord 1168 to a lever 1170 which is pivoted to the frame 1171 and 1172 respectively. The lever 1170 is connected by a cord 1178 to a lever 1180 which is pivoted to the frame 1181 and 1182 respectively. The lever 1180 is connected by a cord 1188 to a lever 1190 which is pivoted to the frame 1191 and 1192 respectively. The lever 1190 is connected by a cord 1198 to a lever 1200 which is pivoted to the frame 1201 and 1202 respectively. The lever 1200 is connected by a cord 1208 to a lever 1210 which is pivoted to the frame 1211 and 1212 respectively. The lever 1210 is connected by a cord 1218 to a lever 1220 which is pivoted to the frame 1221 and 1222 respectively. The lever 1220 is connected by a cord 1228 to a lever 1230 which is pivoted to the frame 1231 and 1232 respectively. The lever 1230 is connected by a cord 1238 to a lever 1240 which is pivoted to the frame 1241 and 1242 respectively. The lever 1240 is connected by a cord 1248 to a lever 1250 which is pivoted to the frame 1251 and 1252 respectively. The lever 1250 is connected by a cord 1258 to a lever 1260 which is pivoted to the frame 1261 and 1262 respectively. The lever 1260 is connected by a cord 1268 to a lever 1270 which is pivoted to the frame 1271 and 1272 respectively. The lever 1270 is connected by a cord 1278 to a lever 1280 which is pivoted to the frame 1281 and 1282 respectively. The lever 1280 is connected by a cord 1288 to a lever 1290 which is pivoted to the frame 1291 and 1292 respectively. The lever 1290 is connected by a cord 1298 to a lever 1300 which is pivoted to the frame 1301 and 1302 respectively.

move these ends forward; the upper ends therefore move back bearing against fingers 112 adapted to push rearward the front parts of the inlet valves 74 thus uncovering 5 the ports 76 of the front of the cylinders and relieving the pressure in front of the pistons so that springs 113 are free to move forward a bar 114 (see Figs. 1, 2 and 7) which moves on guides 115 and is connected to the bar 69 10 moved backward and forward by the pistons. The bar 114 is linked by links 116 to the two halves of the neck ring 64 which thus close ready for the next parison mold to be raised around them.

15 Fast with the fingers 112 are rods 117 beside the valve boxes 75 and these rods are caught by catches 118 (see Figs. 1 and 8) which retain the front ends of the valves in the position last mentioned until the valves 20 are turned by the return movement of the lever 81 due to the spring 88 on the rod 87 when the upper end of the arm 79 of the inlet valve 74 lifts the catch, whereupon the spring 119 moves the front of the inlet 25 valve forward again.

With the parison molds referred to and shown in Figs. 2 and 3 I preferably use a rod or holder as shown in Fig. 13. This consists of a main rod 120 with a spring 30 stud 121 adapted to enter the eye 122 on the mold and with a ring 123 adapted to fit over the top of the mold; to the rod 120 is pivoted a spring pressed shearing rod 124 the forward end of which is provided with a 35 semi-circular knife 125 which coöperates with the ring 123 to shear off the glass when the gatherer considers the amount in the mold sufficient.

40 For making bottles with a "knock up" or indentation in the bottom, a bottom mold 126 is carried on a sleeve 127 sliding on the pillar 67. This sleeve has peripheral teeth 128 meshing with a segment 129 rocked on its pivot by a link 130 engaging a slotted 45 arm 131 fast with the segment and carried by an arm 132 on the bar 69 (see Fig. 2). As therefore the bar 69 moves forward, the mold 126 is raised and swung into the position shown by a pin 133 on one of the halves 50 of the finishing mold 65 which engages a hole in the bottom mold. When the finishing mold opens, the bottom mold is moved down and swung aside out of the way of the parison mold.

55 If it be desired to form a screw thread within the neck of the bottle, I provide a collar 134 on the core rod 14 (see Figs. 7, 14 and 15). This collar is withdrawn from the formed bottle as follows:—Connected to 60 the bar 114 which operates the neck ring is a transverse arm 135 provided with a rack 136 meshing with a pinion 137 on a longitudinal spindle 138 on which is a skew gear wheel 139 engaging a thread 140 on the collar. As therefore the bar 114 moves back

the collar is turned and by reason of its thread it screws itself up into a nut 141 fixed above it as shown in Fig. 14. Or the collar may have an internal thread as shown in Fig. 15 and screw itself up the core rod. 70

It is obvious that various parts may be adjustable so that the machine can make bottles of various sizes and shapes. Moreover the sockets 10 for the molds may be so carried by the table 8 that their height above the table may be varied within considerable limits so that bottles of different sizes may be made at the same time. 75

What I claim is:—

1. In a machine for blowing bottles, a 80 stationary hollow vertical core rod having perforations in it, means for admitting compressed air to the interior of the core rod, means for raising a cylindrical mold containing glass up to the core rod, and means 85 for rotating the mold about its axis.

2. In a machine for blowing bottles, a 90 stationary hollow vertical core rod having perforations in it, means for admitting compressed air to the interior of the core rod, a table, a socket thereon adapted to receive a cylindrical mold, means for raising the table up to the core rod, and means for rotating the mold about its axis.

3. In a machine for blowing bottles, a 95 stationary hollow vertical core rod having perforations in it, means for admitting compressed air to the interior of the core rod, means for raising a cylindrical mold containing glass up to the core rod, means for 100 rotating the mold about its axis, means for lowering the empty mold, a divided finishing mold, and means for closing the finishing mold around the glass hanging upon the core rod. 105

4. In a machine for blowing bottles, a stationary hollow vertical core rod having perforations in it, means for admitting compressed air to the interior of the core rod, a divided neck ring, means for closing the 110 neck ring around the core rod, means for raising a cylindrical mold containing glass up to the core rod, and means for rotating the mold about its axis.

5. In a machine for blowing bottles, a 115 stationary hollow vertical core rod having perforations in it, means for admitting compressed air to the interior of the core rod, a divided neck ring, means for closing the neck ring around the core rod, means for 120 raising a cylindrical mold containing glass up to the core rod, means for rotating the mold about its axis, means for lowering the empty mold, a divided finishing mold, and means for closing the finishing mold around 125 the glass hanging upon the core rod.

6. In a machine for blowing bottles, a stationary hollow vertical core rod having perforations in it, means for admitting compressed air to the interior of the core rod, 130

- means for raising a cylindrical mold containing glass up to the core rod, means for rotating the mold about its axis, means for lowering the empty mold, a divided finishing mold, means for closing the finishing mold around the glass hanging upon the core rod, a bottom mold, and means for raising and lowering the bottom mold as the finishing mold closes and opens.
- 10 7. In a machine for blowing bottles, a stationary hollow vertical core rod having perforations in it, means for admitting compressed air to the interior of the core rod, means for raising a cylindrical mold containing glass up to the core rod, means for rotating the mold about its axis, a collar on the core rod adapted to form a thread in the neck of the bottle, and means for raising and lowering the collar.
- 15 8. In a machine for blowing bottles, a stationary hollow vertical core rod having perforations in it, means for admitting compressed air to the interior of the core rod, a divided neck ring, means for closing the neck ring around the core rod, means for raising a cylindrical mold containing glass up to the core rod, means for rotating the mold about its axis, a collar on the core rod adapted to form a thread in the neck of the bottle, and means for raising the collar as the neck ring opens.
- 20 9. In a machine for blowing bottles, a stationary hollow vertical core rod having perforations in it, means for admitting compressed air to the interior of the core rod, an oil circulation within the core rod, means for raising a cylindrical mold containing glass up to the core rod, and means for rotating the mold about its axis.
- 25 10. In a machine for blowing bottles, a stationary hollow vertical core rod having perforations in it, means for admitting compressed air to the interior of the core rod, an oil circulation within the core rod, a divided neck ring, means for closing the
- 30 neck ring around the core rod, means for raising a cylindrical mold containing glass up to the core rod, means for rotating the mold about its axis, a cylinder, a piston therein, means for admitting air under pressure to the cylinder, and means whereby the movements of the piston close and open the finishing mold.
- 35 11. In a machine for blowing bottles, a stationary hollow vertical core rod having perforations in it, means for admitting compressed air to the interior of the core rod, a cylinder, a piston therein, means for admitting air under pressure to the cylinder, and means whereby the movements of the piston close and open the finishing mold.
- 40 12. In a machine for blowing bottles, a stationary hollow vertical core rod having perforations in it, means for admitting compressed air to the interior of the core rod, a divided neck ring, means for closing the neck ring around the core rod, means for raising a cylindrical mold containing glass up to the core rod, means for rotating the mold about its axis, means for lowering the empty mold, a divided finishing mold, a cylinder, a piston therein, means for admitting air under pressure to the cylinder, and means whereby the movements of the piston close and open the finishing mold and the neck ring.
- 45 13. In a machine for blowing bottles, a stationary hollow vertical core rod having perforations in it, means for admitting compressed air to the interior of the core rod, a table, a socket thereon adapted to receive a cylindrical mold, means for raising the table up to the core rod, means whereby the socket can yield should the mold contain too great a charge, and means for rotating the mold about its axis.

ALBERT BEVERLEY.
